ELECTRIC SWITCH.

Application filed April 19, 1921. Serial No. 462,666.

To all whom it may concern:

Be it known that we, RALPH A. BELMONT and JOHN B. DOWNING, both citizens of the United States, residing, respectively, in the 5 borough of Manhattan, city, county, and State of New York, and Newark, in the county of Essex and State of New Jersey, have invented an Improvement in Electric Switches, of which the following is a specification.

This invention relates to an electric switch and more particularly to that type of electric switch commonly known as a canopy switch. In canopy switches, as is generally 15 recognized, due to the comparatively small space between the inside of the canopy and the wall against which the same is used, it is necessary to have the switch mechanism exceedingly short and hence with extremely 20 limited switch space unless the wall behind the canopy is to be cut away to make provision for the reception of the switch. It is, therefore, preferable, as will be appreciated, to have the inner end of the switch lie within 25 the plane of that portion of the canopy which abuts against the wall in order that no recess or other provision need be made in the wall to receive the switch in placing the canopy in position. The present invention 30 still furthermore relates to that type of switch in which the contact member is actuated by having imparted thereto a reciprocating motion from a revoluble key shaft, as for example as shown and described in 35 Letters Patent No. 811,410, dated January 30, 1906. The present invention relates more particularly to the construction of the contact member in order to obtain the necessary resiliency therein to make the switch 40 operative and consequently practical as well as the manner in which the terminals are secured in the base or body of the switch and against which the resilient contacts are adapted to be moved and bear to complete 45 the circuit through the switch. In carrying out the invention and to obtain the necessary degree of resiliency as well as a contact surface in these contact members, the same are preferably made from a suitable strip of metal secured to a carrier and 50 caused to overlap each other to obtain the

maximum length and the consequent resiliency and the required contact surface, as will be hereinafter more particularly explained.

In switches of this type it has been customary heretofore to extend the lead wires from the base or bottom of the body of the switch and this, as will also be understood, is disadvantageous as requiring an exceedingly short switch body or a recess in the wall to provide for the switch and, as hereinbefore stated, the present invention aims to shorten the switch to the greatest possible extent and in so doing the lead wires 65 are carried from the switch body at the sides thereof, and the invention also relates to the particular manner in which these lead wires and the terminals to which they are secured are connected and mounted in the body of 70 the switch so as to lead from the sides thereof from whence they may be taken to the necessary terminals for completing the circuit to the socket carried by the canopy for a lamp to be used therein, as will also be 75 hereinafter more particularly described.

In the drawing:

Fig. 1 is a central longitudinal cross section of a canopy switch made in accordance with our invention.

Fig. 2 is a cross section on line 2—2, Fig. 1.

Fig. 3 is an elevation showing the operative parts of the switch in one position in which the contact members bear against the terminals.

Fig. 4 is a similar view showing the operative parts in the other position in which the contacts are removed from the terminals.

Fig. 5 is a section on line 5—5, Fig. 3.

Fig. 6 is a section on line 6—6, Fig. 4.

Fig. 7 is a section on line 7—7, Fig. 1, with the operating parts of the switch omitted to show the terminals.

Fig. 8 is an edge view of another form of contact member.

Fig. 9 is a plan of the same, and

Fig. 10 is a cross section illustrating the manner in which the terminals are secured in position in the base or housing of the switch.

Referring to the drawing it will be seen that in carrying out our invention we employ a housing which preferably consists of a base 10 of insulating material and a cap 11 made of metal or other suitable material. In oppositely disposed positions in the outer surface of the base there are longitudinal grooves 12 and the cap is secured to the base by having indentations 13 made 10 in the flange 14 so as to lie within the grooves 12, as is plainly indicated in Figs. 2 and 7 of the drawing.

The cap 11 includes an extension 15 to which there is suitably secured a screw 16 threaded shank 16 adapted to be connected in any suitable manner to a canopy, as for example extending through the same and held in place by a set screw which may be turned down on the screw threaded shank. 20 Extending through and journaled in this screw threaded shank is a key shaft 17. The outer portion of this key shaft is screw threaded as indicated at 18 so as to receive a button 19 through the turning of which 25 the key shaft is revolved to operate the switch. As indicated the inner end of the button 19 is spaced from the outer end of the screw threaded shank by a washer 20 which is preferably a horse-shoe washer and 30 is passed into a groove provided on the key shaft to receive the same.

In the base 10 there are mounted terminals 21 and 22 which, as indicated, are tubular, although as will be understood, they 35 may be of any other configuration and the manner in which these terminals are mounted in the base and the lead wires connected thereto will be hereinafter more particularly described.

40 At the inner end of the key shaft there are flanges or heads 23, 24 connected by a part having oppositely disposed inclined surfaces 25 and 26; and as illustrated these inclined surfaces are employed in oppositely disposed pairs, although, as will be understood, while being employed in pairs any number of pairs may be used instead of the two pairs illustrated, it being understood, however, that multiples of two 45 must be employed and that the faces of the succeeding faces must be oppositely inclined. At their opposite ends the oppositely disposed corners of the surfaces 26 are rounded or recessed as indicated at 27 and in similar 50 positions the surfaces 25 are rounded or recessed as indicated at 28 for the purpose to be hereinafter disclosed. Fitting over the key shaft 17 so as to lie between the inner end of the same and the head 23, 55 we employ a guide member 28', the function of which will also be hereinafter disclosed. As will now be apparent the key shaft 17 is prevented from moving longitudinally in one direction by the head 23 and the guide 60 member 28' and from longitudinal move-

ment in the opposite direction by the washer 20.

We also employ a resilient reciprocating carrier member which is preferably a spring 29 of substantially elliptical configuration 70 having the ends thereof inturned as indicated at 30 and adapted to engage against the inclined surfaces 25 and 26 moving on the same, with the movements limited in one direction by the head 23 and in the opposite direction by the head 24, as illustrated in Figs. 3 and 4. When the inturned ends 30 of the spring carrier member 29 lie against the head 24 the uppermost inturned end in the position illustrated lies in the recess 27, and by imparting a clockwise motion to the key shaft the inturned ends of the spring carrier member are shifted from the inclined surfaces 26 to the inclined surfaces 25, and immediately upon 80 being so transferred the surfaces 25 being inclined in the opposite direction through the resiliency of the spring member the same is caused to travel along the inclined surfaces 25 from left to right as viewed 85 in these figures so as to contact with the head 23, and by imparting another clockwise motion to the key shaft 17 the inturned ends of the spring carrier member are again transferred to the inclined surfaces 26 and the same is returned to its former position. As will now be seen the recessed or rounded corners at the extremities of the inclined surfaces permit this revolute 90 movement of the key shaft in a clockwise direction to actuate the carrier member, and as the opposite corners are square as indicated in Figs. 5 and 6 the key shaft is prevented from turning in a counter-clockwise direction. The guide member 28' extends 95 beyond the head 23 sufficiently far to engage the edges of the resilient member 29, and inasmuch as this guide member is fitted into a recess provided therefor in the housing 10 and is consequently not revolute 100 the resilient carrier member 29 is also prevented from turning by means of the guide member 28'.

The contact member preferably comprises a band of material indicated at 31. This is 115 secured to the resilient carrier member 29 by being passed around the same and secured thereto with an intervening layer of insulating material 32. The ends of the band 31 are offset as indicated at 33 and 34, the one 120 enclosing the other on the outer side of the resilient carrier member, the offset member 33 having an extension 35 overlying the offset portion 34, and similarly the offset portion 34 is provided with an extension 36 125 overlying the offset portion 33 in order to provide the necessary contact surface for the switch. By reference to Fig. 1, it will be seen that these offset portions also provide 130 for the necessary resiliency of the contact

member inasmuch as the entire length of the offset portion is available for the utilization of the spring effect, and as these offset portions cross each other there is a maximum

5 resiliency provided in a minimum space which is necessary in a switch of this type, the resiliency of the offset portion 34 extending from the point A at which it is gripped to the carrier member to the extremity B of
10 the offset portion, whereas similarly the offset portion 33 is provided for obtaining resiliency for its entire length, or from the point A at which it is gripped to the resilient carrier member to the extremity thereof as indicated at D.

Referring to Figs. 8 and 9, it will be seen that instead of constructing the contact member as hereinbefore described, this contact member may consist of a band of metal
20 as indicated at 37 extending around the resilient member 29 and having its extremities formed in arms 38 and 39 which may be suitably slotted to provide for the required resiliency. Obviously other forms of contact
25 members may be employed without departing from the spirit of the invention, although at the present time we prefer to use the contact construction as shown in Figs. 1, 2, 3 and 4.

30 In connecting the terminals 21 and 22 in the base and securing the lead wires therein, it will be seen by reference to Fig. 10 that one end of each of the terminals is flared as indicated at 40 or provided with a head
35 and the terminal passed through a bore provided therefor to receive the same in the base 10 so that a portion of the terminals lies within the recess in the base to permit the resilient contact to bear against the same. When the terminal has been thus placed in the bore provided therefor in the base the lead wire which is preferably a stranded insulated wire as indicated at 41 is
40 passed through the opposite end of the bore in the base and through the terminal to the flared end thereof where it is secured to the terminal by solder or otherwise as indicated at 42, the solder preferably filling the end of
45 the terminal while the remainder of the opening in the housing may be filled with wax or other similar insulating material. In this construction, as will also be seen in Fig. 10, the insulating covering 43 of the lead wire extends into the smaller end of the bore in the housing so as to abut against the adjacent end of the terminal. In this manner it is possible to take the lead wires from the sides of the housing and to permanently
50 connect the ends of the leads in the terminals by securing the leads in the terminals and the terminals in the housing simultaneously.

We claim as our invention:

1. In an electric switch, terminals, a reciprocating member, means for actuating

the same, and a contact member carried by the reciprocating member and having overlapping resilient arms for contacting with the said terminals.

2. In an electric switch, terminals, a reciprocating member, means for actuating the same, a contact member comprising resilient arms extending from oppositely disposed parts of the reciprocating member and crossing each other to obtain a maximum length and resiliency and adapted by the reciprocating member to be moved into and out of contact with the said terminals.

3. In an electric switch, terminals, a reciprocating member, means for actuating the same, and a contact member carried by the said reciprocating member and having overlapping resilient arms with lateral extensions thereon for contacting with the said terminals and adapted to be moved into contact with and away from the same in planes transverse to the direction of travel of the said reciprocating member.

4. In an electric switch, terminals, a reciprocating member, means for actuating the same, a contact member, comprising a band passing around a portion of the said reciprocating member and secured thereto and having arms extending from oppositely disposed parts of the said reciprocating member and crossing each other to provide a maximum length of arm to enable each of the same to resiliently bear against one of said terminals, the said contact member and its arms being moved in planes transverse to the direction of travel of the said reciprocating member.

5. In an electric switch, a casing, a lead terminal let into the casing from one side thereof and extending into the interior of the casing, a lead wire passed through the casing in the opposite direction and into the said terminal therein, and means for securing the lead wire in position in the terminal to maintain both the terminal and the lead wire in place in the casing.

6. In an electric switch, a casing of insulating material having a chamber therein and a transverse opening adjacent the base thereof, a tubular terminal passed into the said opening from one side of the casing, a lead wire passed through the opening in the casing from the other side thereof and into the said tubular terminal, and means for securing the lead wire in the terminal to fix both the terminal and the lead wire in place in the casing.

7. In an electric switch, a casing of insulating material having a chamber therein and a transverse opening adjacent the base passing through the casing and partially intersecting the chamber therein so that the base of the chamber is grooved, a terminal passed into the said opening from one side of the casing, a lead wire passed into the

said opening from the other side of the casing and through the said terminal, and means for securing the lead wire in position in the terminal to maintain both the terminal and lead wire in place in the casing.

8. In an electric switch, a casing of insulating material having a chamber therein and a transverse opening adjacent the base passing through the casing and partially intersecting the chamber therein so that the base of the chamber is grooved, a tubular terminal having an enlarged end and adapted to be passed into the said opening in the casing from one end thereof so as to lie in the groove in the base of the chamber and to extend into the said chamber, a lead wire passed through the opening from the opposite side of the casing and into the said terminal, and means for securing the lead wire in the terminal so as to fix both the terminal and the lead wire in position in the casing.

9. In an electric switch, an insulating casing comprising a base and side walls, and a tubular terminal let into the casing transversely through an opening in a side wall and adapted to receive a lead wire passed transversely through an oppositely

disposed side wall into the said tubular terminal.

10. In an electric switch, an insulating casing comprising a base and side walls, a tubular terminal let into the casing transversely through an opening in the side wall and adapted to receive a lead wire passed transversely through an oppositely disposed side wall and into the said tubular terminal, and means for securing the lead wire in the said tubular terminal at the end thereof adjacent the side wall through which the said tubular terminal is let into the casing.

11. In an electric switch, an insulating casing comprising a base and side walls, a cylindrical terminal having a flaring end let into the casing transversely thereof through an opening provided therefor in a side wall and adapted to receive a lead wire passed transversely through an oppositely disposed side wall of the casing and into the said cylindrical terminal, and means for securing the end of the said lead wire in the said cylindrical terminal at the flared end thereof.

Signed by us this sixth day of April, 1921.

RALPH A. BELMONT.
JOHN B. DOWNING.
